UNITED STATES PATENT OFFICE.

JACOB J. SOUDER, OF WASHINGTON, DISTRICT OF COLUMBIA.

DUMPING-CAR.

SPECIFICATION forming part of Letters Patent No. 715,312, dated December 9, 1902.

Application filed October 9, 1901. Renewed May 7, 1902. Serial No. 106,342. (No model.)

To all whom it may concern:

Be it known that I, JACOB J. SOUDER, a citizen of the United States, and a resident of Washington, in the District of Columbia, have invented a certain new and useful Improvement in Dumping-Cars, of which the following is a specification.

The dumping-car to which my invention relates is one in which the discharge is downward through the bottom of the car, the discharge-openings therein being closed by hinged drop-doors.

My invention consists of certain improvements in this kind of dumping-car, which will first be described in connection with the accompanying drawings, forming part of this specification, and will then be more fully pointed out in the claims.

In the drawings, Figure 1 is a side elevation, partly in vertical section, of a car embodying my improvements. Fig. 2 represents the body of the car, one half in plan and the other half in horizontal section, with a portion of the A center sill removed to expose the parts below. Fig. 3 is an end elevation of the car. Fig. 4 is a section on line 4-4, Fig. 2, omitting the structural details of the end of the car. Fig. 5 is a detached view, in sectional elevation, of a portion of the winding-shaft and the locking-shaft, together with the draw-bar box and bolster-plate. Fig. 6 is a cross-section of a structural detail hereinafter referred to.

The particular car shown in the drawings is a freight-car designed more particularly for the transportation of coke and preferably made of structural steel.

The body A of the car is made of a framing, suitably braced, to which are secured horizontal angle rails or bars, which form the sides and ends of the car. In the sides of the car are a suitable number of sliding doors X, each of which is preferably divided horizontally and longitudinally into two sections, which can slide back and forth independently of each other. These parts are of known construction, and inasmuch as they form no part of my invention they require no further description.

The car is one having fixed inclined bottom sections extending from the longitudinal center line of the car outward over the wheels

thereof and inwardly-inclined bottom sections hinged at their outer edges to the side sills of the car, opening outward from the fixed sections and discharging the contents outside the wheels of the car, in combination with means outside of or below the fixed sections for lowering and raising the hinged sections synchronously, in which respect it resembles the car which is the subject of my Patent No. 676,103, of June 11, 1901; and the fixed inclined bottom sections form, in effect, a central longitudinal metallic support or girder of A shape in cross-section, which extends the length of the discharging portion of the car and is rigidly attached to the end walls of such discharging portion, in which respect it resembles the car which is the subject of my Patent No. 652,930, of July 3, 1900.

Under my present invention the central longitudinal A-shaped girder extends from end to end of the car-body, and it receives, supports, and forms a housing for the draw-bars and their appurtenances, the chain-winding shaft for the hinged bottom sections, and the body-bolster plates for the king-bolts which connect the wheel-trucks to the body of the car. It is, in fact, the center sill of the car. I also locate within the same A-shaped center sill a longitudinal shaft, which is operated from outside the car, preferably from the end of the car, and is designed to actuate and control one or more locking devices located within and secured to the A-shaped sill and adapted to engage the chain-winding shaft at one or more points throughout its length. The central A-shaped sill is shown at A'. It is made, preferably, of sheets of steel properly riveted together and braced. It extends from end to end of the car and at intervals throughout its length is rigidly connected to the body of the car by inclined stay-bars a, which preferably are angle-bars and are formed as continuations of the vertical side frame-bars a' of the body of the car. At the ends of the car it is rigidly secured to the end walls b of the discharging portion of the car.

The side sills of the car consist of channel-bars c. The end sills are shown at d. e represents cross-bars, which extend across between and are connected to the side walls of the car at intervals throughout its length to brace

and strengthen it. At the points where the inclined walls of the A-sill A' pass the truck-wheels W they are slightly raised and given a hood-like form, as indicated at A'', in order 5 to allow all needed play to the wheels. The inwardly - inclined bottom sections, which close the discharge-openings in the car, are shown at B. There are preferably four of these doors, two on either side, and they are 10 hinged on their upper and outer edges to the side sills of the car, as indicated at f. The doors B are lifted so as to close the discharge-openings by means of chains g, in suitable number, attached at one end to the doors and 15 at the other end to a winding-shaft C, which is housed and supported in suitable bearings in the A-sill A' and extends the length of the car. It protrudes through one end of the car, and this protruding end is squared to 20 receive an operating-handle and is provided with a pawl-and-ratchet device h to retain it in wound position, as indicated in Fig. 3.

In order to remove from the winding-shaft the strain which otherwise would come upon 25 it when the doors are closed and the car is loaded, I combine with it one or more locking devices at a point or points within the A-sill A'. I have shown it provided with one such device, but more can be employed, as desired. 30 In the present instance one member of the locking device consists of a star-wheel i, which is fast upon winding-shaft C, and the other member consists of a notched or toothed dog k, housed in and pivoted to a suitable portion of the A-sill A', in a position to overhang the star-wheel i and to be lowered and lifted into and out of engagement with the same. For this purpose its free end is jointed 35 to a link l, which at its other and lower end is 40 in turn jointed to a radial arm m, fixed on and moving with a locking-shaft D, extending lengthwise of the car and housed by and supported in suitable bearings in the A-sill A', in which bearings it can rock, so as to lift and 45 lower the locking dog or dogs k. This locking-shaft protrudes through to the outside of one end of the car, and on this protruding end is fixed an operating handle or lever n. So long as this operating-lever is in locking position, 50 the locking dog or dogs will be forced and positively held down in engagement with the star wheel or wheels i on the winding-shaft. Means—such as, for example, in my allowed application, Serial No. 51,919, filed March 55 19, 1901—should be provided for securing the locking-lever n in this position, so that it may not be tampered with or accidentally misplaced. To open the doors B and discharge the contents of the car, the pawl and 60 ratchet members of the device h of the winding-shaft C should first be disengaged from one another, after which the lever n is moved to rock the shaft D in a direction to lift the locking-dogs k from their star-wheels i. This 65 unlockssimultaneously all the doors B, which at once drop and swing open.

At each end of the car there is secured and housed in the A-sill A' the guide and supporting-frame in which the draw-bar and its appurtenances are mounted. This frame, 70 which may be of any approved structure, is shown in the present instance as consisting of the longitudinal angle-bars o, parallel with one another and at the proper interval apart to afford a frame of the proper width. Between them is secured the channel-bar p, which forms the bottom of the frame. Superposed on the angle-bars o are Z-bars r, which constitute the upper part of the side walls of the frame. Between the contiguous faces of 80 the flanges of the Z-bars and the angle-bars o extend the inner ends or edges of supporting-plates s, which are secured at their outer ends to the inner walls of the A-sill A'. The contiguous flanges of the bars o and r are 85 riveted together and to the interposed edges of the plates s. This makes a trunk or box like frame in which the draw-bar and its appurtenances can be fitted and held.

The bolster-plates of the car also are contained in and housed by the A-sill A'. In this connection I can conveniently use the draw-bar frames for supporting the plates. To this end the rear portions of the angle-bars o of each draw-bar frame are extended 90 beyond the rear ends of the Z-bars r, as indicated in Fig. 5, and on these extended end portions rests the bolster-plate t, which also extends forward between the contiguous flanges of the bars o and r. This plate is 100 riveted securely to the side walls of the A-sill as well as to the bars o and r. In order to brace and support the bolster-plate against upward thrust, I interpose between it and the upper part of the A-sill A' two triangular skeleton 105 angle-bar frames u, located back of the Z-bars r. The inclined sides of these frames closely fit the inclined inner walls of the sill up to their apex or meeting-point. Their bases rest upon the plate t, and they are firmly secured 110 to the plate and sill by riveting or other suitable means. The features last above referred to are illustrated more plainly in the sectional view, Fig. 6, in which u is one of the triangular skeleton frames and t is the bolster- 115 plate attached to angle-bars t', which in turn are secured to the walls of the A-sill. The two frames u are parallel with and at an interval from one another, and in that portion of the plate t which is included between them 120 is formed the hole for the king-bolt, as indicated at w. The triangular opening in each frame u may, for purposes of added strength and stiffness, be closed by a metal diaphragm pierced with openings for the passage of the 125 winding and lock shafts.

Brace-frames similar to frames u may be fitted and secured to the sill A at intervals throughout its length, as shown, for example, in Fig. 4, to secure stability and solidity of 130 structure.

I remark that in lieu of chains for shutting

the doors I may use suitable systems of levers connected to and operated by the winding-shaft.

The central Δ -sill, connected as it is to the 5 sides and ends of the framework of the body of the car, becomes, with the bolster-plates which it carries, the car-bolster. By this construction I dispense entirely with the body-bolsters and longitudinal center or draw sills usually 10 employed. I thus materially reduce the weight of the car and am also enabled to bring the discharge-sections close down over the car-trucks and to more advantageously position and distribute the weight of the contents 15 of the car.

Having described my improvement and the best way now known to me of carrying the same into effect, what I claim herein as new, and desire to secure by Letters Patent, is as 20 follows:

1. In a dumping-car a Δ -shaped center sill extending the length of the car-body, and whose inclined walls constitute fixed inclined bottom sections extending from the longitudinal 25 center of the car outward over the wheels, and doors hinged at their outer edges and resting against the outer edges of the fixed sections when closed, in combination with a longitudinal winding-shaft housed and mounted 30 in said Δ -sill, connecting means between the doors and said winding-shaft, a locking device mounted within the Δ -sill one member

thereof being secured to the sill and the other to the shaft, a longitudinal locking-shaft, connected to and adapted to positively operate 35 the locking device, and housed in and supported by the Δ -sill, and protruding through and beyond the end of the car, and an operating-handle on said protruding end, substantially as and for the purposes hereinbefore 40 set forth.

2. In a dumping-car, a Δ -shaped center sill extending the length of the car-body, doors hinged at their outer edges to the side sills of the car and resting against the outer edges of the inclined walls of the Δ center sill when closed, a longitudinal winding-shaft housed and mounted in the sill connecting means between said doors and winding-shaft, and draw-bar-supporting frames and body-bolster plates 45 50 also housed in and secured to said sills, all substantially as and for the purposes hereinbefore set forth.

3. In a dumping-car, a Δ -shaped center sill extending the length of the car-body, and bolster-plates housed in and secured to said sill, 55 as and for the purposes hereinbefore set forth.

In testimony whereof I have hereunto set my hand this 1st day of October, 1901.

JACOB J. SOUDER.
